DESIGN FOR A PIPE STAND OR SIMILAR ARTICLE

David J. Kirchik, White Plains, N. Y.

Application June 13, 1946, Serial No. 130,677

Term of patent 7 years

(Cl. D85—2)

To all whom it may concern:

Be it known that I, David J. Kirchik, a citizen of the United States, residing at White Plains, in the county of Westchester and State of New York, have invented a new, original, and ornamental Design for a Pipe Stand or Similar Article, of which the following is a specification, reference being had to the accompanying drawing, forming part thereof.

In the drawing:

Fig. 1 is a side view of a pipe stand showing my new design, part being shown in section;

Fig. 2 is a plan view thereof; and

Fig. 3 is an end view thereof shown partly in section.

I claim:

The ornamental design for a pipe stand or similar article, as shown and described.

DAVID J. KIRCHIK.
